US0D1013727S

(12) United States Design Patent (10) Patent No.: US D1,013,727 S
(45) Date of Patent: * Feb. 6, 2024

(54) DISPLAY SCREEN OR PORTION THEREOF WITH AN ICON

(71) Applicant: HUAWEI TECHNOLOGIES CO., LTD., Guangdong (CN)

(72) Inventors: Chao Liang, Shanghai (CN); Anqi Liu, Shenzhen (CN); Ping Song, Shanghai (CN)

(73) Assignee: HUAWEI TECHNOLOGIES CO., LTD., Shenzhen (CN)

() Term: 15 Years

(21) Appl. No.: 29/816,944

(22) Filed: Nov. 26, 2021

(30) Foreign Application Priority Data

May 28, 2021 (CN) 202130324967.6

(51) LOC (14) Cl. 14-04

(52) U.S. Cl.

USPC D14/489

(58) Field of Classification Search

(57) CLAIM

The ornamental design for a display screen or portion thereof with an icon, as shown and described.

DESCRIPTION

The single FIGURE is a front view of a display screen or portion thereof with an icon showing our new design. The outer dash-dot broken lines in the drawings illustrate the display screen or portion thereof and form no part of the claimed design.

1 Claim, 1 Drawing Sheet
